United States Patent Office

Des. 183,320
Patented Aug. 5, 1958

183,320

PUFFED TEXTILE FABRIC

Douglas D. McCord, New York, N. Y., assignor to Chicopee Mills, Inc., a corporation of New York

Application September 3, 1957, Serial No. 47,572

Term of patent 14 years

(Cl. D92—1)

Fig. 1 is a plan view of a puffed textile fabric showing my new design;

Fig. 2 is a view taken along lines 2—2; and

Fig. 3 is a side edge view.

I claim:

The ornamental design for a puffed textile fabric, as shown.
